UNITED STATES PATENT OFFICE.

ALBERT S. NEWBY, OF KANSAS CITY, MISSOURI.

UPPER AND LOWER PLATE FOR FIRE-BOWLS.

SPECIFICATION forming part of Letters Patent No. 379,594, dated March 20, 1888.

Application filed March 28, 1887. Serial No. 232,808. (No model.)

To all whom it may concern:

Be it known that I, ALBERT S. NEWBY, a citizen of the United States, residing at Kansas City, in the county of Jackson and State of Missouri, have invented certain new and useful Improvements in Upper and Lower Plates for Fire-Bowls; and I do hereby declare the following to be a full, clear, and exact description of the invention, such as will enable others skilled in the art to which it appertains to make and use the same.

My invention relates to an improvement in the lower fire-bowls for stoves; and the objects of the invention are to provide upper and lower plates for the fire-bowl, with a series of circular grooves or depressions on the faces of said plates adjacent to the edges of the bowl, whereby one or more of the series of rings formed by said grooves or depressions may be removed by breaking either from the outside or inside of said plates, thereby preparing the plate, when occasion demands, for use upon any-sized fire-bowl.

The invention consists, primarily, in a plate having a series of grooves or depressions on its face, and means for its attachment, as will be more fully described.

The invention further consists in the features of construction and combinations of parts, as will be hereinafter more fully explained and claimed.

In the drawings, Figure 1 is a perspective view of a fire-bowl having my improvements applied. Fig. 2 is a detail view of the top plate.

Corresponding parts in the figures are denoted by the same letters of reference.

Referring to the drawings, A represents the fire-bowl, which, as shown, is flaring, so that the coal will be fed to the bottom thereof, and will not lodge or hang to the sides of the bowl.

B represents the bottom plate for supporting the lower end of the fire-bowl, and to which the stationary grate is attached. This plate is circular in form, and is provided with a central opening of sufficient size to admit the stationary grate C. The said plate is formed on its upper and lower sides or faces with a series of circular rings or depressions, on any one of which the lower edge of the fire-bowl is adapted to rest, and is provided with inwardly-projecting lugs, to which the stationary grate is bolted or otherwise firmly secured.

The movable grate D fits in a central opening in the stationary grate, and is adapted to be shaken and overturned, as usual. It is preferable to so arrange the shaking-grate that its load will be discharged toward the rear instead of the front end of the stove, so that all possibility of live coals or ashes falling on the floor of the room in which the stove is located is avoided.

E represents the upper plate, which is provided on its upper face, a short distance from its inner edge, with a circular groove or depression, e, and between said groove e and said outer edge, on both its upper and lower faces, with a series of depressions, f. On its under face, near its inner edge, said plate is provided with a groove, g, as shown. On the upper face of said plate, between the groove e and the inner edge of the plate, are provided a series of depressions, h. When the fire-bowl is a large one, it fits in the groove e, and that portion of the plate between the groove e and the inner edge is broken off. When a smaller bowl is employed, the plate is reversed or inverted, and that portion between the groove e and the outer edge of the plate is broken off. The said plate is provided with holes or openings which are adapted to receive bolts i, passing through lugs j, formed on the upper edge of the fire-bowl, for securing the bowl and plate together.

Having fully described my invention, what I claim as new, and desire to secure by Letters Patent, is—

1. The herein-described fire-bowl plate, consisting, essentially, of an annular plate provided with breaking grooves near its inner and outer edges, whereby it may be increased in size interiorly and decreased in size exteriorly to suit stove-bodies of different sizes, substantially as set forth.

2. The herein-described fire-bowl plate, provided with seats for the end of the fire-bowl, arranged alternately on the under and upper sides of the plate, and having breaking grooves near its inner and outer edges, whereby the plates may be fitted to stoves of different sizes, substantially as set forth.

In testimony whereof I have affixed my signature in presence of two witnesses.

ALBERT S. NEWBY.

Witnesses:

W. D. THORNBURGH,
BESSIE E. YOUNG.
